United States Patent

Des. 240,462
Patented July 6, 1976

240,462

MEDICINAL APPLICATOR OR THE LIKE

Barry H. Dash, Englewood Cliffs, N.J., assignor to American Home Products Corp., New York, N.Y.

Filed May 8, 1974, Ser. No. 468,050

Term of patent 14 years

Int. Cl. D24—04

U.S. Cl. D83—12 A

FIG. 1

FIG. 3

FIG. 4

FIG. 5

FIG. 2

FIG. 1 is a front elevational view of a medicinal applicator or the like showing my new design;

FIG. 2 is an exploded side elevational view;

FIG. 3 is a top plan view;

FIG. 4 is a top plan view with the cover removed; and

FIG. 5 is a bottom plan view.

I claim:

The ornamental design for a medicinal applicator or the like, substantially as shown.
